CLAIM

The ornamental design for a shower accessory cup, as shown, and described.

DESCRIPTION

FIG. 1 is a perspective view of a shower accessory cup;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

The broken lines shown in the figures represent portions of the shower accessory cup that form no part of the claimed design.
